(Cl. D56—4)

To all whom it may concern:

Be it known, that I, Louis Gregory, a subject
of the King of England, residing at London, W.C.
1, England, have invented a new, original and
ornamental Design for a Combination Radio
and Phonograph Cabinet, of which the following
is a specification, reference being had to the ac-
companying drawings, forming part thereof.

Fig. 1, is a front perspective view and Fig. 2 is
a rear perspective view of a combination radio
and phonograph cabinet, showing my new de-
sign.

I claim:

The ornamental design for a combination radio
and phonograph cabinet, as shown.

LOUIS GREGORY.
